Primary Examiner — Karen E. Eldridge Powers*Assistant Examiner* — Kimberly Barnes(74) *Attorney, Agent, or Firm* — John K. Park; Park Law Firm(57) **CLAIM**

The ornamental design for a cap, as shown and described.

DESCRIPTION

FIG. 1 is a side perspective view of a cap showing my new design;

FIG. 2 is a front elevation view thereof;

FIG. 3 is a rear elevation view thereof;

FIG. 4 is a top plan view thereof;

FIG. 5 is a side elevation view thereof; and,

FIG. 6 is a bottom plan view thereof.

The broken line showing of environment is for illustrative purposes only and forms no part of the claimed design.
